UNITED STATES PATENT OFFICE

160,748

TOY ANIMAL FIGURE

Robert E. Smith, New Rochelle, and Edward G. Kean, New York, N. Y.; said Kean assignor to said Smith

Application June 4, 1949, Serial No. 3,064

Term of patent 14 years

(Cl. D34—2)

To all whom it may concern:

Be it known that we, Robert E. Smith, a citizen of the United States, residing at New Rochelle, New York, and Edward G. Kean, a citizen of the United States, residing at New York, New York, have invented a new, original, and ornamental Design for a Toy Animal Figure, of which the following is a specification, reference being had to the accompanying drawing, forming part thereof.

We claim:

The ornamental design for a toy animal figure, as shown.

ROBERT E. SMITH.
EDWARD G. KEAN.
